KNITTED SOCK

John R. Killian, Jr., Whitfield, Reading, Pa., assignor to K. W. Knitting Mills, Inc., Mohnton, Pa.

Filed Feb. 14, 1966, Ser. No. 1,033

Term of patent 14 years

(Cl. D2—331)

FIG. 1 is a side elevational view of a knitted sock, showing my new design; and

FIG. 2 is an enlarged, fragmentary view of a portion thereof.

I claim:

The ornamental design for a knitted sock, substantially as shown.
